UNITED STATES PATENT OFFICE.

JAMES HATTON, OF NEW YORK, N. Y.

IMPROVEMENT IN METALLIC HANDLES.

Specification forming part of Letters Patent No. **73,804**, dated January 28, 1868.

To all whom it may concern:

Be it known that I, JAMES HATTON, of the city, county, and State of New York, have invented a new and useful Improvement in Metallic File-Handles; and I do hereby declare that the following is a full, clear, and exact description thereof, which will enable those skilled in the art to make and use the same, reference being had to the accompanying drawings, forming part of this specification.

This invention relates to a new and improved method of constructing file-handles and handles used for similar purposes, whereby files or screw-drivers and other tools of a similar nature of different sizes may be used without changing the handle, and whereby the tool is much more securely fastened in the handle, while the handle itself is indestructible.

The invention consists in making the handle of metal in two parts and in packing the handle with some elastic material for holding the file or other tool, and in fastening the parts together, as will be hereinafter described.

Figure 1 is a view of the handle complete. Fig. 2 is a cross-section of the same through the line *x x*. Fig. 3 is a longitudinal section of Fig. 1 through the line *y y*.

Similar letters of reference indicate corresponding parts.

The handle is hollow and cast or swaged in two parts, A and B. These parts are fastened

together by a screw-nut or ferrule, C, and by a screw, D, as seen in dotted lines, Fig. 1.

There is also a steady-pin in the butt-end of the handle, as seen at *f*.

In the neck of the handle there is a recess for the shank of the file or other article, which is packed with leather or some other elastic material, as seen in Figs. 2 and 3. The elasticity of this packing prevents the shank of the file or other article from working out, while the packing itself is fastened in its place by the enlarged portion *g*, which fits into the recess in the handle.

These handles may be either cast of brass or iron, or they may be swaged out of sheet metal; and it will be seen that a handle may be made in this manner so that almost every sized file or screw-driver or other tool of a similar kind will fit.

What I claim, and desire to secure by Letters Patent, is—

Constructing handles for files, screw-drivers, and for other purposes, of metal with elastic packing, substantially in the manner herein shown and described.

The above specification of my invention signed by me this 10th day of June, 1867.

JAMES HATTON.
